graphie m. b. H., Berlin, Germany, a corpora-
tion of Germany

Application June 22, 1932, Serial No. 618,621
In Germany June 29, 1931

3 Claims. (Cl. 250—11)

In direction finding work it is well known that errors are incurred which are due to the simultaneous reception of the horizontal and the vertical components of an electric field (so-called nocturnal effect). Now, attempts have been made to eliminate these errors by the use of purely vertical antennæ with horizontal leads brought down to the receiver in lieu of a loop or coil. In connection with arrangements of this kind it is necessary to carefully screen off the horizontal portions of the leads in order that they themselves may not pick up energy from the outside field. However, unless special ways and means be adopted a considerable part of the horizontal component will be picked up. The manner in which the several components of a wave affect the absorption system and my novel method of and means for preventing said effects to act on the radio apparatus connected therewith will be understood from the following specification and therefrom when read in connection with the drawing, throughout which like reference characters indicate like parts, and in which:

Figures 1 to 3 inclusive show various antenna systems which include the novel features of my invention.

The manner in which the components of the field of the wave affect the absorption system will be briefly explained by reference to Figure 1.

A1 and A2 denote vertical aerials. Their leads Z1 and Z2 to the receiver R are perfectly screened electrically by a shield or screen S. Due to the horizontally polarized electrical field, however, a potential difference will arise in the horizontal portions of the screening S which are indicated by the + and — symbols in the drawing. Owing to inevitable capacities between the shielding and the antennæ A1 and A2 (indicated by the dotted lines in the drawing), potential differences will be set up also between the aerials, and these potential differences cause the flow of a current in the leads brought down to the receiver outfit representative of the horizontal component of the field.

According to the present invention the system is so arranged that couplings between the antennæ and the leads brought to the receiver will be symmetric relative to each other and to the shielding. Such a scheme is illustrated by way of example in Fig. 2. The couplings L1, L11 between the antennæ are as shown of the inductive and of the symmetrical kind, though it is not essential that they be inductive since other coupling methods may be used. Potential differences

across the ends of the horizontal portions of the shielding S, in the presence of symmetrical arrangement of the antennæ result in no potential differences across the ends of the coils L1 and L11. As a result, no current will be produced in the leads Z1, Z2, brought down to the receiver R.

Fig. 3 shows an embodiment of the basic idea for unsymmetrical antennæ. The electrical coupling between the antenna A2 and the shielding means S is compensated by the condenser C2 connected as shown between the antenna and the shield S. The electrical mid-point of the coupling inductance in A2 is also connected to S.

The means and ways hereinbefore disclosed for the purpose of compensating the electrical horizontal component are useful for all kinds of direction finder apparatus using antennæ having vertical and horizontal portions. It is, for example, immaterial whether the direction finder consists of two antennæ with revolvable leads or whether four antennæ are stationarily disposed at the corners of a square and united with a goniometer by stationary leads. The grounding or even the burying of the shielding means for the leads is not sufficient for over-coming the night effect for the reason that potential differences are always able to be built up upon the screens. The invention is especially valuable for short-wave direction finders, though it is applicable with the same amount of success to direction finders working with longer waves.

Inasmuch as it is indispensable that both antennæ result in exactly the same amplitude in the receiver for correct bearings for it is only the difference in the amplitudes that is utilized for direction finding, it is therefore important that either the antennæ and the couplings be made equal or else it is necessary to make the couplings variable.

I claim:

1. A short wave antenna system including a vertical antenna, a horizontal conductor unsymmetrically coupled thereto, and means for preventing the horizontal component of an electrical wave from setting up current in said antenna comprising a shield for said horizontal conductor and a variable condenser connected between said shield and said vertical antenna for balancing any unbalanced capacitive coupling between said antenna and said conductor by way of said shield.

2. A short wave antenna system including a plurality of vertical antennæ, each of said antennæ including, an inductance, horizontal conductors terminating in inductances coupled to said first named inductances, a conductive

shield completely enclosing said conductors and all of said inductances, there being openings in said shield to permit connection between each of said antennæ and its inductance, a connection 5 between a point in each of the inductances in said antennæ and said shield, and a variable condenser connected between each antennæ and said shield to compensate for any unbalanced capacitive coupling between said antennæ and said 10 shield.

3. A short wave antenna system including a pair of vertical antenna each including an inductance unsymmetrically located therein, means for coupling said antenna to radio apparatus 15 comprising an inductance coupled to each of said

antenna inductances, a horizontal conductor connected between a terminal of each of said last named inductances, horizontal conductors connecting the other terminals of each of said last named inductances to radio apparatus, 5 means for shielding said horizontal conductors and said coupling inductances including a metallic shield completely enclosing said conductors and said inductances, there being openings in said shield for said vertical antennæ, and means 10 for compensating any unbalanced coupling between said antennæ and said shields comprising a variable condenser connected between each of said antennæ and said shield.

ALBRECHT GOTHE. 15
